ATTORNEYS

UNITED STATES PATENT OFFICE.

ANNA ROTHSTEIN, OF CHICAGO, ILLINOIS.

UNDERGARMENT.

Application filed April 1, 1927. Serial No. 180,209.

My invention relates to improvements in undergarments, such as brassières and the like, and it consists in the combinations, constructions, and arrangements herein described and claimed.

An object of my invention is to provide a construction which will permit of the use of non-elastic shoulder straps, while permitting the shoulder straps to move to accommodate the movements of the body.

A further object is to provide a construction having elastic means which will permit the shoulder straps to move with the body, these elastic means being normally hidden by the garment itself.

A further object is to provide a garment having elastic means for permitting the movement of the shoulder straps which will permit the use of inelastic shoulder straps that can be detached and washed.

Other objects and advantages will appear in the following specification, and the novel features of the invention will be particularly pointed out in the appended claim.

My invention is illustrated in the accompanying drawings, forming part of this application, in which

Figure 1 is a figure showing one embodiment of my invention,

Figure 2 is an enlarged view showing the shoulder strap as attached to the garment,

Figure 3 is a section along the line 3—3 of Figure 2, and

Figure 4 is a modified form of the device.

In carrying out my invention, I make use of an undergarment such as a brassière. On the inside of the garment, below the upper edge thereof, I provide a pocket 2 which is made by taking a piece of suitable material and stitching it at the side edges, as shown at 3, to the body of the garment. The upper edges are preferably turned over and hemmed as at 4. A piece of elastic webbing 5 is secured at its lower edge within the pocket, the lower edge of the pocket being preferably formed into a hem and a row of stitching 6 being provided for holding the webbing in the hem. The webbing 5 is continued out of the pocket and is provided with a button 7.

A shoulder strap 8, which may be a ribbon or other suitable band, is provided with a buttonhole 9 arranged to receive the button 7 and this strap may be fastened in front in

any suitable way, as by a buttonhole similar to that shown at 9.

From the foregoing description of the various parts of the device, the operation thereof may be readily understood. The normal position of the garment and the shoulder straps is that shown in Figures 1 and 2. In this position, very little of the elastic band is visible. When, however, through stooping or reaching, strain is placed on the shoulder band, the elastic 4 will give so as to permit the strap to accommodate itself to the movement of the wearer. When the body resumes its normal position, the strap will again assume the position shown in Figure 2, the major portion of the elastic being concealed by the pocket.

The use of such device gives flexibility to the shoulder strap, and at the same time it permits the use of a non-elastic shoulder strap which can be taken off and washed. It adds but little to the cost of the garment, and, since the elastic band is largely concealed, it in nowise detracts from the appearance.

It frequently happens that in the construction of garments such as the present, the garment is made up of a number of individual parts. These parts are sewed together and the seams are covered with stripping. The stripping serves two purposes; namely, as a means for covering the seams so as to prevent the seam from contacting with the body of the wearer, and as a concealing means. In Figure 4 I have shown the stripping 11 used in lieu of the pocket 2. The stripping 11 is arranged to cover a seam 11'. In this construction the elastic portion 4 is secured between the stripping 11 and the garment by stitching 6. The stripping 11 is cut off near the top of the garment for permitting the attaching of the shoulder strap 8 to the button 7. Thus it will be seen that the stripping 11 serves the purposes above mentioned, and at the same time provides a pocket for the elastic portion 4.

In both cases, the elastic band is largely concealed but it serves the purpose of permitting the movement with a non-elastic shoulder strap which would not be possible if the shoulder strap were connected rigidly to the garment.

I claim:

The combination of a non-elastic shoulder strap having a buttonhole in one end thereof,

an undergarment having seams therein and stripping sewed over said seams, said stripping having stitches relatively near the edges thereof for securing the stripping to the undergarment, certain of said stripping terminating short of the upper edge of said undergarment and having an open end to form a pocket, an elastic band disposed within the

10 pocket and arranged to project out of the pocket, a button secured to the exteriorly projecting portion of the elastic band and arranged to enter the opening in said shoulder strap, and a line of stitching transversely across the stripping and one end of the elastic band for securing the latter.

ANNA ROTHSTEIN.
